IMPROVEMENT IN CENTRIFUGAL PUMPS.

E. HALL COVEL, OF NEW YORK, N. Y.

Letters Patent No. 60,145, dated December 4, 1866.

SPECIFICATION.

TO ALL WHOM IT MAY CONCERN:

Be it known that I, E. HALL COVEL, of the city, county, and State of New York, have invented a new Improvement in Pumps; and I do hereby declare that the following is a full, clear, and exact description thereof, which will enable others skilled in the art to make and use the same, reference being had to the accompanying drawings, forming a part of this specification.

The pump embraced in the present invention consists of a turbine or other suitable water-wheel at the lower end of the pump-cylinder or tube, in combination with a vertical, spiral, or screw-shaped elevator, placed above said water-wheel, and revolving in conjunction therewith, in such manner that the water forced or drawn into the pump-cylinder by the action of the water-wheel, will be taken by the said screw-elevator, and carried up or raised through the pump-cylinder or tube, from whence it will escape at its upper end through any suitable discharge nozzle or pipe, and conducted to any locality or point desired.

In addition to the above, the present invention also consists in forming at the upper end of the pump-cylinder, above the screw-elevator, a square-shaped chamber, by means of which the "twirl" or circular motion that the water has, as it leaves the screw-elevator, will be neutralized or overcome before the water escapes or is discharged from the pump, as will be herein more fully explained.

In the accompanying plate of drawings my improvement in pumps is illustrated.

Figure 1 being a central vertical section through the pump-cylinder, with the screw-elevator and water-wheel in side elevation; and

Figure 2, a transverse horizontal section taken in the plane of the line $z z$, fig. 1.

A, in the drawings, represents the pump-cylinder or tube, the length of which, as well also as its size, diameter, &c., will depend upon circumstances and the work which the pump has to perform. B, a vertical shaft extending down through the centre of the pump-cylinder, or tube A, turning in suitable bearings of the same at each end. C, a water-wheel of any suitable construction, secured to the lower end of shaft B, so as to turn, or revolve within the tube or cylinder A, in a horizontal plane; water passing to this wheel, C, through the spaces D, about the lower bearing of the shaft B. Around the shaft B, above the water-wheel C, is formed a spiral or screw-shaped flange, E, extending up through the pump tube or cylinder A, which flange, E, fits within the said cylinder A, sufficiently close to secure the raising of the water by it, which passes from the water-wheel thereto, at its lower end, while at the same time no injury will occur to it, if sand, &c., should be carried up through the pump-cylinder with the water being forced through it by the combined action of the wheel and screw-elevator. Above the upper end of the screw-elevator a square-shaped chamber, H, is formed, for the purpose of breaking or overcoming the "twirl" or circular motion of the water as it leaves the upper end of the screw-elevator. I, a pipe or nozzle, at the upper end of pump-tube, through which pipe the water is to escape from the pump, and to be conducted to any desired point or locality by making the proper connections therefor. By the combination of the water-wheel and screw-elevator, arranged substantially as herein described, I am enabled to raise water with great facility and with the expenditure of a power or force but little, if any, exceeding that required to operate either the wheel or elevator separately, while a result is secured equal to the action of both, if used separately.

Having thus described my invention, what I claim as new, and desire to secure by Letters Patent, is—

In pumps the combination of a water-wheel and screw-elevator, when arranged substantially as and for the purpose described.

I also claim an angular or irregularly-shaped chamber, in combination with a pump-cylinder in which water or other fluid is elevated by a spiral or vertical motion, substantially as described for the purpose specified.

The above specification of my invention signed by me this 21st day of November, 1866.

E. HALL COVEL.
